UNITED STATES PATENT OFFICE.

GEORGE PAYNE, OF ORILLIA, ONTARIO, CANADA.

HOSPITAL-BED.

1,132,614.

Specification of Letters Patent. Patented Mar. 23, 1915.

Application filed March 21, 1914. Serial No. 826,150.

To all whom it may concern:

Be it known that I, GEORGE PAYNE, of the town of Orillia, in the county of Simcoe, in the Province of Ontario, Canada, have invented certain new and useful Improvements in Hospital-Beds, of which the following is the specification.

My invention relates to improvements in hospital beds and the object of the invention is to devise means whereby a patient may be easily moved from a lying to a sitting position without jar or exertion on the part of the patient or attendant and in which means are provided for receiving through the bed 15 excreta and for easily removing the same and it consists essentially of a bed frame, a mattress frame divided into three sections, the head section being swung between the side bars of the bed frame at its inner end, 20 the center section being swung between the head section intermediately of its length and a foot section being pivotally connected to the center section at its inner end, a rock shaft supported in the main frame, depending arms secured to the rock shafts, normally horizontal arms extending from the ends of the rock shafts beneath the side bars 25 of the center and head sections, a link connecting the depending arms, a revolving drum mounted beneath the frame, a crank for operating the same and a cord connection between the drum and depending arms, an orifice formed in the center mattress section, a pivoted frame secured at one end beneath the same and provided with a suitable fastening clip at its opposite end and having guide-ways, and a receptacle designed to be slid laterally within the guide-ways beneath the orifices of the mattress as herein, 30 after more particularly explained by the following specification.

Figure 1, is a sectional elevation of a hospital bed constructed in accordance with my invention. Fig. 2, is a similar view to Fig. 1 showing the mattress frame raised to carry the patient to the sitting position. Fig. 3, is a plan view. Fig. 4, is a cross sectional view on line $x-y$ Fig. 3. Fig. 5, is a perspective detail of the parts shown in Fig. 4. Fig. 6, 0 is a detail of the mattress closing plug.

In the drawings like letters of reference indicate corresponding parts in each figure.

A is a bed frame provided with side bars A'.

5 B is a mattress frame comprising a head section B', center section B² and foot section

B³. The head section B' is swung between the side bars A' of the bed A at B⁴. The center section B² is swingably connected to the head section B' at B⁵ and the inner end of the foot section B³ is swingably connected at B⁶ to the center section B². The outer end of the foot section rests upon the cross bars A³ forming part of the bed frame. 60

B⁷ and B⁸ are rocking shafts journaled in the frame of the bed beneath the head and center mattress sections. 65

B⁹ and B¹⁰ are normally depending arms extending from the rocking shafts B⁷ and B⁸ respectively. 70

B¹¹ and B¹² are arms extending in a normally horizontal direction from the ends of the shafts B⁷ and B⁸ and beneath the side bars of the mattress sections B' and B², the ends of such arms being provided with suitable friction rollers contacting with such side bars. 75

C is a drum journaled in suitable bearings secured to the side bars of the bed. The drum C is provided with an operating crank 80 C' and ratchet C² with which the swinging gravity dog C³ engages to hold the drum C in a stationary position.

E² is a cord secured at one end to the drum C from whence it extends downwardly to the arm B⁹. 85

E is a link connecting the arms B⁹ and B¹⁰ together.

F is an ordinary mattress divided into three sections F', F² and F³ corresponding to the head, center and foot sections of the mattress frame. The center section F² is provided with an orifice F⁴ provided with a mattress plug closure F⁵ (see Fig. 6). 90

It will be readily seen that when it is desired to change the position of the patient from the lying to a sitting position or vice-versa all that it is necessary to do is to rotate the crank C' and drum C so as to wind the cord E² thereon thus drawing the arms B⁹ and B¹⁰ from the position shown in Fig. 1 to the position shown in Fig. 2. When it is desired to deposit the excreta all that it is necessary to do is to remove the plug F⁵. 95

H is a frame hinged at one end to the center section of the bed frame at H'. The frame H is provided with side guides H² and an eye pin H⁴ extending through the slot B¹³. 100

It will be understood that the center, head and foot sections of the mattress frame are provided with suitable spring mattress por-

tions. The center section is formed by a board having a central orifice B¹² and a slot B¹³, a leather cover being provided which is suitably laced to the edges of the spring 5 mattress fabric.

3 is a receptacle provided with a flange 3' slidably held in guide-ways H², the upper end of the receptacle bearing against the center mattress section around the orifice B¹².

H³ is a hook pivotally connected to the top of the center section and designed to engage with the eye H⁴ projecting upwardly through the slot B¹³ thereby locking the 15 frame H in a horizontal position.

In order to remove the receptacle when necessary, all that is required to do is to release the hook H³ and swing the frame H downwardly toward the inclined position 20 (see dotted lines in Fig. 4) when the receptacle 3 may be easily slid therefrom.

J is a tension spring connected at one end to the bed frame and at the opposite end to the arm B⁹. The spring J serves to compensate to a certain extent to the weight of 25 the patient.

K is a screen frame comprising sections K', K² and K³ hinged together, the end section K³ having a hinged connection to the 30 bed frame.

From this description it will be seen that I have devised a very simple form of hospital bed by which a patient may be easily removed from a lying to a sitting position without discomfort to the patient and without undue labor on the part of the attendant.

What I claim as my invention is—

In a hospital bed the combination with a bed frame provided with the usual side bars, of a mattress comprising a head, center and foot sections, said head and foot sections being pivotally connected to said center section, arms secured to the sides of said head section and extending beyond the inner end thereof, pivotal connections between the inner ends of said arms and the side bars of the frame, a bell crank pivoted to said side bars and having one end bearing against said head section, a similar bell crank having one end bearing against said center section, a link connecting the free ends of said bell crank and a winding drum secured to said frame and connected to the free end of said first mentioned bell crank, as and for the purpose specified.
